VALVE

Peter A. Gaglio, Chicago, George E. Hansen, Elmwood Park, and Walter L. Krueger, Villa Park, Ill., assignors to Crane Co., Chicago, Ill., a corporation of Illinois

Filed Sept. 23, 1968, Ser. No. 13,678

Term of patent 14 years

Int. Cl. D23—01
U.S. Cl. D23—38

FIG. 1

FIG. 2

FIG. 3

FIG. 4

FIGURE 1 is a top plan view of a valve showing our new design;

FIGURE 2 is a bottom plan view thereof;

FIGURE 3 is a side elevational view thereof; and

FIGURE 4 is an end elevational view thereof.

The dominant features of our design reside in the portions shown in full lines.

We claim:

The ornamental design for a valve, as shown and described.
